UNITED STATES PATENT OFFICE

ALBERT KALO, OF COLUMBUS, OHIO

SAFETY VALVE FOR GAS BURNERS

Application filed January 7, 1930. Serial No. 419,174.

This invention relates to automatic gas cut-offs for use in connection with burners of gas stoves or the like and has for its principal object the provision of an automatic cut-off for gas burners, whereby the accidental extinguishing of the flame will cause a valve to operate, stopping the flow of gas from the main supply pipe to the burner.

Another object of the invention is the provision of a device of the class mentioned having a thermostatic rod disposed within the heating zone of the burner and operated, upon expansion, to hold the valve in an open position. When the flame is extinguished the thermostatic rod contracts permitting the valve to close and shut off the gas flow.

A further object of the invention is to provide an automatic gas shut-off which is simple in construction, cheap to manufacture and positive in its operation.

With these and other objects in view the invention consists in certain novel features of construction, combination and arrangement of parts, the essential features of which are hereinafter fully described in the specification and pointed out in the appended claims.

For a further understanding of the invention reference is to be had to the following description and accompanying drawings, wherein:

Figure 1 is a plan view of a gas burner and associated valve mechanism employed in the present invention.

Figure 2 is a vertical longitudinal sectional view taken on the line 2—2 of Figure 1.

Figure 3 is an enlarged vertical sectional view taken through the air inlet end of the mixing conduit and the auxiliary automatic valve.

Figure 4 is a horizontal sectional view taken on the line 4—4 of Figure 3 disclosing in plan the auxiliary valve member in its active position.

Figure 5 is a similar view showing the valve in its inactive position, and

Figure 6 is a view showing a slightly modified form of the invention.

Often the flow of gas to the burners becomes accidentally extinguished either by low

pressure or by a gust of wind flooding the room or place with deadly gas fumes, which in a great many cases has proved fatal to the occupants. Children frequently open such valves or again the supply of gas in the main or conduits supplying the burner may for certain reasons be discontinued which, as above stated, permits the gas to escape unless controlled by the main valve.

Referring more particularly to the drawings, the numeral 1 designates a gas burner structure of the type commonly employed in connection with gas burning stoves, ranges, hot water heaters and the like. This structure, which comprises a burner head 2, a gas supply pipe 3, a manually operated main valve 4, and a mixing conduit 5, into which gas from the supply pipe 3 is delivered by the opening of the valve 4, in which conduit air from the atmosphere is intimately mixed with the gaseous fuel and delivered in commingled form to the burner head for combustion purposes. The conduit 5 includes a large mixing chamber 6 at the forward end thereof which includes an apertured front wall 7. This wall in this instance is made separate from the conduit 5 and is secured thereto by means of screws or other fastening devices 8. The amount of air entering the mixing chamber 6 is governed, as usual, by controlling the positions of a disk 9 to enlarge or diminish the effective areas of the apertures at the walls 7 and 9 through which the air enters the mixing chamber. The wall 7 is provided with a longitudinally and axially extending nipple 10, which is formed to include a longitudinally extending bore 11. The outer end of this bore is enlarged and threaded for the reception of the inner end of the valve casing 12 of the manually operated valve 4, while the opposite end of the casing 12 is threadedly received within an opening formed in the supply pipe 3. The casing 12 is, as usual, provided with a rotatable valve plug 13, formed with an opening 14 which registers with aligned passages 15 provided in the casing 12. When these parts are positioned as described, gas may pass from the supply pipe 3 to the manually operated valve 4 and thence into the nipple 10.

Figure 2 is a vertical longitudinal sectional view taken on the line 2—2 of Figure 1. Figure 3 is an enlarged vertical sectional view taken through the air inlet end of the mixing conduit and the auxiliary automatic valve.

Figure 4 is a horizontal sectional view taken on the line 4—4 of Figure 3 disclosing in plan the auxiliary valve member in its active position.

Figure 5 is a similar view showing the valve in its inactive position, and

Figure 6 is a view showing a slightly modified form of the invention.

section 10 for admittance into the mixing chamber 6. The valve plug 13 is operated by the usual handle 16 and is adapted to be retained in its positions of adjustment by a spring 17 all of which are customary constructions.

The auxiliary valve mechanism, which comprises the present invention, forms a safety attachment for any standard form of burner construction and is designated in its entirety by the numeral 18. Preferably, this mechanism comprises a valve plug 19, having a passage 20 extending diametrically through it, and so arranged that by rotating the valve plug 19 the passage 20 is brought into and out of registration with the passage 11. Mounted rigidly upon the valve plug 19 is a plate or extension 21, whereby it is actuated. The lower end of the valve plug 19 is threaded for the reception of a retaining nut 22 for holding the valve member in an operative relation within the end of the nipple 10. Pivotally connected to the extension or plate 21 as at 23 is the inner end of an actuating lever 24. The lever 24 includes a forwardly and outwardly protruding arm 25 which extends through the mixing chamber and through registering openings formed in the wall 7 and the disk 9, the said arm terminating in an exterior finger engaging portion 26 located contiguous to the manually operated valve member 4. It will be seen that by pushing forward upon the arm 25 the valve member 19 will be rotated about its pivotal axis to an open position. Such movement of the lever is normally restricted by means of a coil spring 27 which has its inner end attached as at 28 to the plate 21 and its outer end connected to the wall 7. The valve member 19 is positioned normally, as shown in Figure 5, to restrict gas flow through the longitudinal bore 11 of the nipple section 10, thus preventing the flow of gas into the mixing chamber independently of the manual valve 4.

To control the automatic functioning of the valve member 19 there is provided a thermostatic rod or element 29 of a material preferably of metal which responds quickly in the matter of expansion and contraction, to the influence of the heat generated by the combustion of gas in the burner head. One end of the thermostatic rod 29 is rigidly secured by means of a screw 30 to the inner wall of the tubular passage 31 formed, as is customary, in the burner head 2. The other end of the rod 29 is adapted to engage the arcuate surface 32 of the plate 21 arranged at right angles to the vertical axis of the valve member 19. The arcuate surface 32 forms a portion of a circle and has the same axis as that of the valve member 19 and is of such length as to have a rubbing engagement with the end of the rod 29 during part of its rotating movement with the valve member 19. The

plate 21 is also formed with a cut away portion leaving a surface 33 spaced from the rod 29 when the valve is in its inactive position thus preventing undue rubbing action and wear upon the end of the rod. To keep the outer end of the rod 29 in its position relative to the disk the conduit 5 is provided with a bearing 34 through which the rod 29 is positioned for sliding movement when expanded and contracted during the functioning of the burner structure.

By the provision of the disk 21 and its positioning with respect to the rod 29 it will be seen that the valve member may be rotated around its axis without disturbing the location of the rod 29. By the provision of the set screw 30, the operating positions of the rod 29 may be governed or set to function as desired in response to the heat developed around the burner head. Except for the set screw 30 the rod 29 may expand and contract without interference and for this reason it is slidably received for free and unobstructed movement in an opening formed in the wall of the passage 31.

In view of the foregoing it will be seen that the present invention provides a simple, substantially automatic auxiliary valve structure for use in combination with gas burners whereby uncontrolled escape of gas from such a burner is effectively precluded. To operate the burner to admit of gas flow it is first necessary to open the valve member 4 as usual. Following this the finger portion 26 of the lever 24 is forced inwardly so that the valve member 19 will be rotated aligning the passage 20 with the bore 11 of the nipple 10. The opening of the bore 11 allows gas to flow into a mixing conduit 5 where it is intermingled with air and delivered to the burner head in combustible proportions. Combustion may then be started at the burner head by any suitable means so that heat is immediately developed at the burner in the vicinity of the inner end of the rod 29. This heat acts upon the rod 29 to effect its expansion.

As a matter of fact, the operation is substantially instantaneous as after combustion has been initiated at the burner head, the expansion of the rod 29 operates to maintain the valve member 19 in its open position by impinging against the arcuate surface 32 at which time the finger portion 26 may be released and the burner structure will then operate in the normal manner. The closing of the valve 4 arrests combustion at the head 2, so that the rod 29 will contract, and become slightly spaced from the arcuate surface 32 allowing the spring 27 to move the valve member 19 to its normal position of bore closure. It will therefore be evident that the mere opening of the valve 4 will not permit of gas escape unless combustion is initiated at the burner head.

The various parts above described are lo-

cated comparatively close together and are conveniently arranged so that the operator can readily actuate the handle 16 of the valve 4 and also engage the finger piece 26 with the same hand and thus actuate the parts controlled by said finger piece while lighting the burner with the other hand in cases where a pilot light is not employed. The auxiliary valve mechanism and the thermostatic rod 10 are located within the burner structure and are thus protected from injury and from being tampered with. The auxiliary valve mechanism has the advantage of being extremely simple in construction and requires no adjustment of parts after once being installed.

In the modified form of the invention disclosed in Figure 6 the rotatable disk 35 provided upon the valve member is formed with a shoulder 36 with which the end of the thermostatic rod 29 engages after being expanded by the heat of the burner. This construction differs from the preferred form of my invention in that instead of the rod 29 impinging the periphery of the disk, the same is free to expand longitudinally to form a positive stop preventing the closing of the valve until the thermostatic rod has cooled or contracted, freeing the shoulder 36 and permitting the closing of the valve due to the action of the spring 27.

While there has been shown and described what I consider to be the preferred form of my invention, it is to be understood that I do not wish to limit myself to the precise structure or details herein shown and described, but that changes, alterations and modifications as come within the claims may be resorted to when desired.

0 What is claimed is:

1. In a gas burner, a gas and air inlet conduit having an air mixer casing at one end thereof, a valve in said casing for controlling gas flow therethrough, said valve including a rotatable port controlling member having a head at one end, manually operating means connecting said head and leading to the exterior of said air mixer casing, a thermostatic rod within said conduit having one end 5 thereof seated within the heating zone of said burner and its other end in close proximity to said head and operative when expanded by the heat from the burner to impinge upon said head to hold the valve in an open position, said head and thermostatic rod being positioned to one side of the outlet of said valve so as not to interfere with the free gas flow issuing from said outlet.

2. In a gas burner, a gas and air inlet conduit having an air mixer at its outer end, a plug valve positioned within said mixer for controlling the gas flow therethrough, said valve having its outlet end arranged in alignment with the longitudinal axis of said conduit, a head provided at one end of the

plug valve, means for effecting the operation of said valve from the exterior of said mixer and conduit, and a thermostatic element within said conduit responsive to the heat of the burner and engaging said head for holding said valve in an open position, said element being positioned to one side of the longitudinal axis of said conduit.

3. In a gas burner, a mixing conduit, a gas supply pipe entering said mixing conduit, a valve in said pipe, an automatically closed auxiliary valve in the inner end of said supply pipe and positioned within the outer end of said mixing conduit, a rotatable port controlling member in said auxiliary valve including an arcuate enlargement at one end arranged exterior of said valve, means for effecting the actuation of said auxiliary valve from the exterior of said mixing conduit, a thermostatic element within said conduit responsive to the heat of the burner and adapted to engage with said enlargement to hold said valve in open position, means for automatically closing said auxiliary valve upon the contraction of said thermostatic element, said element being positioned to one side of the longitudinal axis of said conduit.

In testimony whereof I affix my signature.

ALBERT KALO.
